UNITED STATES PATENT OFFICE.

MICHAEL KIRSHNER, OF LYNCHBURG, VIRGINIA.

APPARATUS FOR EXTRACTING OIL.

SPECIFICATION forming part of Letters Patent No. 761,686, dated June 7, 1904.

Application filed February 8, 1902. Serial No. 93,186. (No model.)

To all whom it may concern:

Be it known that I, MICHAEL KIRSHNER, a citizen of the United States of America, and a resident of Lynchburg, in the county of 5 Campbell and State of Virginia, have invented certain new and useful Improvements in Extracting Oil, of which the following is a specification.

This invention relates to certain improvements in apparatus for extracting oil from cotton-seed meal; and the object of the invention is to produce a machine of this character which will be capable of receiving the meal through a suitable hopper or chute and extract the oil preferably by a continuously-operating mechanism, so that the meal may be delivered at one portion of the machine and acted on, so as to extract the oil therefrom and deliver the meal and oil separately.

In my preferred form, as illustrated in the accompanying drawings, the machine is of a rotary character and receives the meal into various pockets in a revolving drum, and the latter, through the aid of plungers and cams, acts to squeeze the meal and deliver the oil into any suitable receptacle, while the meal (now very dry and in the form of compact cakes) may be delivered onto an endless apron, from which the cakes are transferred to any predetermined place.

In the accompanying drawings, which represent the preferable embodiment of my invention, Figure 1 is a vertical cross-section of my apparatus. Fig. 2 is a vertical section taken at right angles to that shown in Fig. 1. Fig. 3 is a detail sectional view of one of the plungers and "pockets" on a much larger scale. Fig. 4 is an elevation from the inside of one of the end frames, showing the partial cylindric casing in section. Fig. 5 is a vertical section of one of the side frames and part of the cylindrical casing, and Fig. 6 is a sectional detail of a portion of one of the plungers on a much larger scale.

Referring now to the details of the drawings by numerals, 1 and 2 represent a pair of side frames on opposite sides of the machine, which are supported by standards 3 and 4 of any desired construction. Situated between

these frames 1 and 2 is a casing 6 of cylindrical form, and the side frames are bolted to this casing, as clearly shown at 7 in Figs. 2 and 5. This casing does not extend entirely around the space inclosed by the side frames 1 and 2, but has a gap of preferably 55 about one-fourth of its circumference, as shown in Figs. 1 and 4, for a purpose to be hereinafter described. Within this casing 6 is rotatably supported a hollow drum 8, provided with annular extensions forming journals 9 and 10, which pass through and are journaled in openings in the side frames. The journal 10 is somewhat longer than its companion 9 and has a worm-wheel 11 keyed thereto, and this worm-wheel meshes with a 65 worm 14, operated through the shaft 17 and pulleys 15 and 16, to which power may be applied in any convenient manner.

The aforesaid hollow drum 8 is formed with a series of radially-disposed pockets or openings 19, which extend toward the central opening and are open at the periphery of said drum. In each of these pockets is a plunger 20, arranged to slide in and out of the pockets, each plunger being formed T-shaped, as 75 shown in Fig. 3, and the stems 21 of the plungers 20 are arranged to slide in similarly-shaped parts 22 of the pockets 19. All of the pockets are open at each end, and all of the plungers have trunnions 24 formed on both of 80 their ends, which trunnions are for the purpose of supporting rollers 25, which may be held in place by means of plates 26 and screws 27, as shown in Figs. 2 and 6.

The side frames 1 and 2 are provided with 85 annular grooves or recesses 30 and 31, and the lower portions of these grooves or recesses are channeled out to form oil-pockets 32 and 33, these pockets being provided with tubes 34 and 34^a to deliver the oil from the oil-pockets 32 and 33 into any desired receptacle or storage-chamber. (Not shown.)

The aforesaid grooves or pockets 30 and 31 are each provided with an annular shoulder 36, (see especially Fig. 5,) and cams 38 and 95 39 are secured to the side frames 1 and 2 by means of screws 40. The cams are of the peculiar shape illustrated in Fig. 4, from which

figure it will be seen that the cams, beginning with the point marked *a*, gradually grow larger from the axis of rotation until the point *b* is reached, and from this last-mentioned 5 point the cams are of uniform size around to the point *c*, where it will be noticed that a hump *d* is provided. The cams are formed in the manner illustrated, so as to act on the rollers journalized on the plungers in order that the 10 plungers may be forced outward in the peculiar manner hereinafter described.

On the top of each of the plungers 20 is bolted a pressure-plate 35, which is formed in the peculiar manner illustrated in Figs. 3 and 15 6. Each of these plates is longitudinally grooved, as seen at 36, and these longitudinal grooves lead into the larger openings 37 through the small passages 38, and between the pressure-plates 35 and the plunger 20 a large 20 opening 38^a is left, into which the oil which is extracted from the seed or meal may pass. Each of the pressure-plates 35 is also provided with tubes 40, which rotate with the 25 plungers and pressure-plates and afford a means of permitting the oil to pass from the openings 39 into the oil-pockets 32 and 33, as will be seen from inspecting Fig. 2. As there 30 is great pressure on these pressure-plates 35, I prefer to strengthen them by lugs 42, as 35 clearly seen in Figs. 3 and 6. The surfaces of each of these pressure-plates 35 is covered with camel's-hair mats 41, which are usually employed for this purpose, these mats being of such a nature as to furnish the proper strength, and yet permit the oil to sift through them.

In order to keep the seed or meal in a heated condition while the oil is being extracted therefrom, I form a water or steam jacket around it, which may be seen in Figs. 1, 2, 4, 40 and 5. In the form in which I prefer to make it the heating fluid may be forced through an inlet 44, from which it passes through the circuitous passage 46 and out of the outlet 47, (see Fig. 2;) but this of course may be varied 45 to suit the pleasure of the manufacturer.

In order to properly deliver the seed or meal to the pockets, I employ a hopper or any suitable seed-chute, which, as shown in my drawings, consists of a delivery-tube 50, which 50 is secured immediately over the hollow drum 6 and between the side frames 1 and 2, as seen in Figs. 1 and 2.

I have hereinbefore described the cylindrical casing as being open for about one-fourth of its circumference, and this cylindrical casing and the side frames 1 and 2 are beveled off, as shown in Figs. 1 and 4, and to the upper beveled part 51 I secure a scraper 52, formed with a knife-edge, and to the lower beveled 60 part 53 I secure a suitable inclined guide 54, which is arranged to deliver cakes from the pockets onto an endless apron 56, as shown in Fig. 1, so that the cakes may be carried away from the machine and delivered at any 65 suitable point.

The operation of my apparatus may be described as follows: Power being applied to the pulley 16, the hollow drum 8 is given rotary movement through the medium of shaft 17, worm 14, and worm-wheel 11, and the endless belt 56 is driven in any suitable manner. (Not shown.) The cotton-seed meal is delivered to the tube 50 in a heated state, and as the hollow drum 8 is rotated and the pockets therein pass underneath said seed-tube 50 the meal is progressively fed into said pockets. At such times as the pockets are under said meal-tube 50 the rollers on the plungers are acting on the lowest part of the cam 39, and hence the plunger, then under the feed-tube 50, is in the lowest position in its pocket, as clearly shown in Fig. 1. As the drum is slowly rotated the pockets pass from under said feed-tube 50, and the rollers traveling around the cam 39 are gradually forced outward, carrying with them the plungers, so as to gradually compress the meal and squeeze the oil therefrom through the openings 36, 37, and 38 into the larger opening 38^a, and as soon as the hollow drum is rotated to bring the feed-tubes of each plunger into or rather below a horizontal line the oil contained in 80 said openings 38 is delivered from the tubes 40 into the pockets 32 and 33, from which it passes through the tubes 34 and 34^a into any 85 suitable receptacle or storage-chamber. From an inspection of the cams shown in Fig. 4 it will be seen that after the point *b* is reached the cam is of uniform size until the point *c* is 90 reached. This is for the purpose of forming the cotton-seed meal into a compact cake and holding it in such form for a long enough period of time to retain such form. As soon as the rollers reach the point marked *c* they 95 are forced outward through the medium of the hump *d*, and this outward action of the rollers of course forces the plungers outward, carrying with them the pressure-plates, camel's-hair mat, and the dried cake. The hump on the cam is of the proper height to push the 100 cake outward far enough to be shoved off of its camel's-hair mat by the scraper 52. The cake then falls by gravity, and as its falls onto the inclined guide 54 it is guided to fall 105 onto the endless apron 56, by which it may be delivered to any suitable place. After the 110 rollers pass the outward incline of the hump *d* the plungers are permitted to recede on the inward incline of the hump by gravity, as in a full-sized machine the plungers are quite 115 heavy.

From the foregoing and the accompanying drawings it will be seen that I have invented a continuously-operating machine which is admirably adapted to its purpose of receiving the cotton-seed meal and treating it so as to deliver the oil therefrom into any desired 120 receptacle and at the same time form the meal itself into compact dried cakes, which being formed under great pressure and held there 125 130

for some little time retain their shape so well as to permit them to be shipped to places, when they may further utilized.

I have shown in the accompanying drawings 5 what I now believe to be the preferable embodiment of my invention, but of course do not limit the following claims to the apparatus as herein disclosed, but regard my invention as being broad enough to cover any 10 changes suggesting themselves to one who studies the foregoing specification or drawings.

What I claim as new is—

1. In apparatus of the character described, a 15 series of movable receptacles for receiving the material being treated, means operated by the movement of the receptacles for compressing the material therein and for holding it compressed, whereby the material becomes "set," 20 substantially as described.

2. In apparatus of the character described, a movable element having a plurality of receptacles or pockets, means for feeding material therein, and means for compressing the material in the plurality of receptacles or pockets 25 as the aforesaid element moves, the said means also holding the material compressed for a portion of time whereby it becomes "set," substantially as described.

3. In apparatus of the character described, a movable element having a plurality of receptacles or pockets, means for feeding material therein, means for compressing the material in said receptacles or pockets as the aforesaid element moves, said means also holding the material compressed for a portion of time whereby said material becomes "set," and means arranged to eject the material from said receptacles or pockets after compression, substantially as described.

4. In apparatus of the character described, a series of movable receptacles for receiving the material being treated, means operated by the movement of the receptacles for compressing the material therein and holding it compressed 45 whereby it becomes "set," said means comprising a plunger arranged to have the liquid forced through it, substantially as described.

5. In apparatus of the character described, a 50 casing, a rotatable drum contained in said casing and having a series of pockets therein, plungers working in said pockets, means for operating said plungers to compress the material therein and to hold it compressed for a period of time whereby the material becomes 55 "set," an opening through which the material may be ejected, a scraper for scraping off the material and a guiding-board for directing the material scraped off, substantially as described.

6. In apparatus of the character described, a 60 casing, a rotatable drum in said casing having a series of receptacles for receiving the material to be treated, pressure-plates acting in said receptacles and having openings therein

through which the liquid is forced and means in the casing coacting with the openings in the pressure-plates for conducting away the material passing through said openings, substantially as described.

7. In apparatus of the character described, a casing, a body having a plurality of openings or pockets therein, movable means located within said openings for compressing material therein, said movable means having oil ducts 75 or tubes leading therefrom, and a pocket in the casing for collecting said oil, substantially as described.

8. In apparatus of the character described, a body having a plurality of openings or pockets therein, movable means located within said openings for compressing material therein, said movable means having oil ducts or tubes leading therefrom, a side frame having an oil-collecting pocket, and a delivery-tube leading from said last-named pocket, substantially as described.

9. In apparatus of the character described, a side frame having an oil-collecting pocket therein, a drum capable of rotation and having a plurality of pockets or openings therein, movable means for compressing material therein, said movable means having oil ducts or passages for delivering oil from said pockets into the pockets in said side frame, substantially as described.

10. In apparatus of the character described, a pair of side frames, one of which has an oil-collecting pocket, a drum capable of rotation and having a plurality of pockets or openings 100 therein, movable means for compressing material therein, said movable means having a passage for conveying the oil from said pockets to the pocket in the side frame, and means for ejecting the material from said pockets, 105 substantially as described.

11. In apparatus of the character described, a movable body having receptacles or pockets adapted to have material compressed therein, plungers movable in said pockets, means for operating said plungers, and for ejecting the material after compression, said plungers working independently of each other, substantially as described.

12. In apparatus of the character described, 115 a drum having a plurality of pockets or openings therein adapted to receive material to be compressed, plungers in said pockets or openings, means for rotating the drum, and means for moving said plungers independently of 120 each other, said means being arranged to eject the material after compression, substantially as described.

13. In apparatus of the character described, the combination of a casing, a suitably-supported rotatable drum, means for rotating said drum, a series of pockets or receptacles in said drum, a series of plungers working in said pockets or receptacles and arranged to have the oil pressed therethrough, means for 130

forcing said plungers outward, a passage in the casing for collecting the oil pressed through said plungers, and means for ejecting the material from said openings or receptacles, substantially as described.

14. In apparatus of the character described, the combination of a casing, a suitably-supported drum having a series of pockets or receptacles therein, means for rotating said drum, a series of plungers working in said pockets or receptacles and arranged to have the oil pressed therethrough, cams and cam-rollers for actuating said plungers, a passage in the casing for collecting the oil pressed through said plungers, the said plungers also being arranged to eject the material after compression, and an endless apron for conducting away the ejected material, substantially as described.

15. In a device of the character described, a receptacle for receiving material being compressed open at its ends, a plunger working therein and having its ends projecting out of said open ends, and means for acting on said projecting ends, substantially as described.

25 16. In a device of the character described, a receptacle for receiving material being compressed open at its ends, a plunger working therein, and having its ends projecting out of said open ends, rollers on said ends, and means for acting on said rollers to operate said plunger, substantially as described.

17. In apparatus of the character described, a casing, a drum rotatable in said casing and having a series of pockets therein having open ends, plungers working in said pockets and having their ends projecting out of said open ends, and means for acting thereon, substantially as described.

40 18. In apparatus of the character described, a casing, a drum rotatable in said casing and having a series of pockets therein having open ends, plungers working in said pockets and having their ends projecting out of said open ends, rollers on said plungers and means acting on said rollers for operating said plungers, substantially as described.

19. In apparatus of the character described, a casing having a chamber therein, an oil-conducting passage in the walls of said chamber 50 extending partially around the latter, a rotatable drum in said casing having a series of

pockets therein, plungers in said pockets, means for forcing said plungers outward, and means for conducting the oil from said drum to said oil-conducting passage, substantially as described.

20. In apparatus of the character described, a casing comprising two side frames having cams thereon, a rotatable drum in said casing having a series of pockets therein, and plungers in said pockets, the said plungers coacting with said cams, substantially as described.

21. In apparatus of the character described, a casing comprising two side frames having cams thereon, a rotatable drum in said casing having a series of pockets therein, and plungers working in said pockets and having rollers on their ends, the said rollers coacting with said cams and thereby actuating the plungers, substantially as described.

22. In apparatus of the character described, the combination of a rotatable drum having a series of pockets therein, means for feeding material in said pockets, means for compressing material therein and for holding it compressed whereby it becomes "set," and a casing containing the rotatable drum and having a steam or water jacket for heating the interior surface of the casing and thereby heating the material contained in the pockets, substantially as described.

23. In apparatus for extracting oil, the combination of a casing having an oil-passage around the same, a drum rotatable in said casing and having a plurality of openings or pockets therein, movable means located within said openings or pockets for compressing the material conveyed therein and thereby extracting the oil, said movable means having ducts or tubes leading therefrom and conveying the oil to the passage in the casing, the said pockets receiving the material and said movable means acting progressively to express the oil from the material whereby the apparatus continuously acts to express the oil, substantially as described.

Signed by me at Lynchburg, Virginia, this 6th day of February, 1902.

MICHAEL KIRSHNER.
